UNITED STATES PATENT OFFICE.

JACOB FELBEL, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

Application filed April 8, 1926. Serial No. 100,556.

My invention relates to typewriting machines and has for its chief object the provision of new and improved means for and methods of duplicating typewritten copies, the term "duplicating" being used in the broad sense of producing any desired number of typewritten copies of matter at a single operation.

To the above and other ends which will hereinafter appear, my invention consists in the methods of producing duplicate copies and also in the features of construction, combinations of devices and arrangements of parts hereinafter described and particularly 15 pointed out in the claims.

A primary feature of my invention resides in a method of making the work sheet or sheets ready for use or adjusting them in place, which method broadly stated involves 20 adjusting the paper on the platen apart from or separated from the machine, the platen with the adjusted paper thereon being then applied to the machine in condition to receive the writing without any further adjustment 25 or manipulation of the paper. In carrying out my invention in the present instance I have made use of a work sheet or work form of the character disclosed in the patent to E. Z. Lewis No. 932,713, dated August 31, 1909. 30 Said work sheet, sometimes referred to as a multiple work or form sheet, is of the style which is wound or wrapped, together with a carbon or duplicating sheet, a plurality of times around the platen, each complete 35 "wrap", so to speak, or winding being devoted to one work form only, so that the number of reproductions depends upon the number of times the sheet is wrapped on or around the platen. To carry out my idea conveniently I provide a platen which is constructed 40 to be readily detached from its bearings in the carriage of the typewriting machine and applied to a conveniently disposed table or support on which are a supply of the 45 work sheets or forms and the duplicating material or carbon paper. The platen preferably carries a clamp or gripping device by which the work forms may be connected to the platen, so that when it is rotated by a hand 50 piece or handle associated with the table, the clamped work sheet and the duplicating material are wound in place, the rotation being continued until the work sheet is fully wrapped on, after which the platen is 55 placed in the typewriting machine in readi-

ness for the writing to be begun. It will be seen, then, that my invention contemplates both the reproducing method involving the removal of the platen from the typewriting machine, the adjusting of the paper in place 60 thereon and the return of the platen with the paper to the typewriting machine ready for writing, and also means for practicing the method of carrying it out, said means comprising an improved platen bearing enabling 65 the platen readily to be detached from the typewriting machine, and a bearing or support apart from said machine combined with turning devices whereby the platen may conveniently be rotated or handled in adjusting 70 the paper outside of the machine so that the platen and paper may be put in the typewriting machine all ready for use.

However, as will more clearly appear from what follows, it is to be understood 75 that the practising of my invention is not confined to the preferred method and means of carrying it out as outlined above. The platen, for example, need not be applied to an outside or separate bearing and rotated 80 by a handle to wind the paper thereon, but instead, as appears from certain of the figures of the accompanying drawings, the platen may be manipulated or rotated to wind on the paper without the assistance of 85 any outside means or mechanism. Moreover, my invention contemplates within its scope the preparation of a considerable number of platens with work sheets or form sheets in place thereon, which platens may 90 be distributed to the operators from a common source of supply, such prepared platens replacing other platens carrying work forms on which the typewriting has been completed. 95

My invention will be described and explained more fully and in detail in connection with the accompanying drawings, wherein

Fig. 1 is a fragmentary front elevation, 100 partly in section, of the platen carrier or carriage and platen of a typewriting machine constructed in accordance with my invention.

Fig. 2 is a transverse sectional view taken 105 on a plane indicated by the section line 1—1 in Fig. 1 and looking in the direction of the arrows at said line.

Fig. 3 is a corresponding sectional view taken on the section line 2—2 in Fig. 1. 110

Fig. 4 is a detached perspective view of the right-hand platen head or member.

Fig. 5 is a fragmentary end elevation, partly in section, of a platen support and 5 platen and rotating devices for winding a work sheet on the platen.

Fig. 6 is a side elevation of the parts shown in Fig. 5.

Fig. 7 is a fragmentary sectional view 10 taken longitudinally of the platen and showing the latching mechanism at the left-hand end thereof.

Fig. 8 is a fragmentary perspective view 15 of the left-hand end portion of the platen, detached.

Fig. 9 is a view illustrating the manipulation 20 of the platen to wind on the form sheet or work sheet by hand, thus dispensing with the winding mechanism shown in Figs. 5 and 6.

Fig. 10 shows the platen, with the work sheet and carbon paper fully wound and in 25 the hand of the operator, ready to be placed in the typewriting machine, whether thus wound in accordance with Fig. 9 or Figs. 5 and 6.

As a matter of convenience I have shown 30 my invention applied to the carriage and platen of the Remington No. 12 typewriting machine, although, of course, it is to be understood that the invention may be readily made use of in connection with the platens of other typewriting machines. The Remington No. 12 platen is equipped with 35 platen release mechanism for affording disconnection between the platen and its line spacing ratchet wheel, which mechanism is of the general character disclosed in the patent to Woodward No. 784,369, granted 40 March 7, 1905. However, this platen release mechanism employs long grippers which extend from the line spacing ratchet wheel into the interior of the platen to a considerable distance, and since such grippers 45 would interfere with the ready detachment of the platen from its bearings in the machine, which ready detachment is essential to the carrying out of my invention in the best way, I have found it necessary to modify the platen disconnecting mechanism of 50 the No. 12 Remington machine, so as to provide short grippers which do not extend within the body of the platen. The use of 55 this new style of gripper requires certain other changes in the regular construction, although the principle thereof is retained.

Referring first to the construction disclosed in Figs. 1 to 8 inclusive of the drawings, there are mounted above the top plate 60 1 of the No. 12 Remington machine, front and rear fixed guide rails, of which only the rear rail 2 is shown herein. Said rails support a carriage comprising a truck and a shiftable platen frame, the truck comprising 65 a rear bar or rail 3 from which extend for-

ward side or end bars 4, the end bars being connected at their front end portions by a front bar or rail not shown herein. Shiftably mounted on the truck by means including links 5 and 5^a is a platen frame comprising 70 a cross bar 6 that connects the lower portions of end bars 7, which at their upper end portions are connected by a cross rod 8.

Mounted on the carriage is a rotary platen comprising a core 9 of wood and a sheath 75 10 of rubber, or the like. The platen is provided with circular end plates 11 screwed at 11^a, Fig. 7, to the core and having their peripheries covered by the rubber sheath. Each end plate is formed with a diametrical 80

rib or spline 12 which engages with grooves in cooperating members supported on the opposite ends of the carriage, whereby the platen is detachably supported in said carriage. The said cooperating members are of 85 different constructions and mountings and will be separately described. The left-hand member 13 is cylindrical in shape and formed at its right-hand face with a groove or seat 14 which receives the associated rib 12. At 90

its left-hand end the member 13 is provided with a hub 15 which is bored to receive the inner end of a stub shaft or platen axle 16 secured in place by a cross pin 17. On the 95 outer end of the stub shaft is the usual finger wheel 18. The mounting of the stub shaft substantially corresponds with that found in the No. 12 Remington machine. The shaft is enclosed within a tube 19 which terminates at its inner end in a flange 20.

The outer face of the tube at its right-hand portion is threaded through a plate 21 secured by screws 22 to the inner face of the associate end bar 7, said end bar being 100 formed with an opening 23 through which the tube passes. Said tube is secured in place or clamped to the plate 21 and the end bar by a clamping nut 24. A wire spring 25 is coiled 105 around the exterior of the tube and provides a bearing or bumper, the spring normally 110 resting on the case shift stop screw 26 which projects slightly above the bottom of an opening 27 in the end bar 4. At the top of 115 said opening is a corresponding downwardly projecting stop screw 28 which cooperates with the coiled spring bumper 25 to limit upward shifting movements of the platen in the usual manner.

Both ends of the platen are provided with 120 spring pressed latches for preventing lateral displacement of the platen relatively to its supporting members. Each latch, as best

appears from Figs. 1, 7 and 8, comprises an arm 29 pivoted at 30 to bearing ears 31 on the companion plate 11. The arm 29 is 125 seated in a cut-out 32 formed in the end of the platen behind the associated plate 11 and at its lower or inner end is provided with an outward extension 29^a which extends 130 outward through an opening 33 in the end

plate 11 and into a notch or under-cut 34 in the associate rib 12. The extension or tongue 29^a of the left-hand latch also cooperates with a cut-out or slot-way 35 formed in the inner face of the member 13. A coiled spring 36 seated in a circular depression 37 fits loosely at its outer end over a projection 38 on the latch and tends constantly to press said latch outward and maintain it inter-seated both with the notch 34 and with the slot in the associate connecting member, as 35. The construction is such that the latches maintain the platen in proper centered relationship with its supports and for connection 15 to rotate therewith. Each latch is provided opposite its pivot 30 with an outwardly projecting finger piece 39 which may be pressed to overcome the associate spring 36 and withdraw the latch from operation, as hereinafter 20 more fully set forth.

The rib or spline 12 of the right-hand plate 11 interseats with a slot-way 40 (Fig. 3) formed diametrically in a cylindrical co-operating member 41, said member at its 25 inner end being provided with a slot-way 42 which receives the tongue 29^a of the associate latch, in correspondence with the slot-way 35 of the left-hand member 13. At its right-hand end portion the member 41 is 30 provided with a flange 43, and both the flange and the right-hand end portion of the body of the member 41 are hollowed out as indicated at 44 to fit over the inner end of a head or clutch-supporting member designated as a whole by the numeral 45. Said member is best known in its entirety in Fig. 4. It comprises a cylindrical body portion 46, a circular flange 47 projecting from the middle of the body portion, and a right- 35 wardly extending hub 48. The member 45 is centrally bored as indicated at 49 and is provided with diametrically opposite slots or seats 50 and also with a transverse kerf or cut-out 51. It is adapted to be detachably 40 secured to the member 41 by screws 52. Adapted to bear rotatively on the body portion 46 to the right of the flange 47 is an annulus 53, the outer periphery of which is formed with the usual set of line spacing 45 ratchet teeth 54. The toothed annulus or ratchet wheel 53, 54 is held from outward displacement by a plate 55 abutting against the outer end of the body portion 46 to which it is suitably secured. A flanged tube 50 57 passes through the right-hand end bar 7 and is locked thereagainst by a check nut 58. Fitting in the inner end of the tube or bearing 57 is the hub 48 of the member 45, while the outer end portion of said tube has 55 fitted into it a short or stub tube or housing 59 which covers the right-hand platen shaft or axle 60. Outside the tube 59 said axle receives the usual finger wheel 61 to which the tube 59 is secured. Surrounding the 60 tube 57 is a coiled wire covering or bumper 65

62 corresponding to the spring bumper 25 at the left. Said bumper 62 rests on the right-hand lower screw stop 26, and is adapted when the platen is shifted, to contact with the upper screw stop 28, the screw 70 stops projecting through the opening 27 in the right-hand end bar 4.

Normally the ratchet wheel 53, 54 is clutched to the platen so that when the usual hand actuated line spacing pawl co-acts 75 with said ratchet wheel it will force the platen to turn therewith. Said ratchet wheel also cooperates with the usual detent roller 63 to maintain the platen in line spacing 80 positions and prevent accidental rotary displacement thereof. The clutching means between the line spacing wheel 53, 54 and the platen comprise a pair of grippers 64 which are seated in the cut-outs 50 in the member 45. These grippers are formed with slots 85

65 providing arms which embrace the inner flange of the ratchet wheel, and are also formed with notches or rounded portions which are adapted to bear on the bottoms of the seats 50. The inner end portions of the grippers are provided with inclined or cam edges 66 which cooperate with like edges 67 on the opposite end portions of a head 68 which is secured to the inner end of the shaft 60 and fits slidably in the slot 51 of the member 45. A wire spring 69 housed within the tube 59 is coiled around the right-hand end portion of the shaft 60; the inner end of said spring reacting against a ring 90

or annulus 70 which fits on the shaft 60 and is limited in its leftward movement by a pin 71 projecting down through the tube 57. The construction is such that the spring 69 tends constantly to press the shaft 60 right- 95 ward in its bearings and normally maintains the cam head 68 in effective position against the grippers 64, as shown in Fig. 1. In this position the sides of the slots 65 of the grippers bear effectively against the opposite faces of the ratchet wheel 53, 54, clutching 100 said ratchet wheel so that it will turn the platen when the line spacing mechanism is actuated. It will be seen that the connection of the ratchet wheel with the platen is through the grippers 64, the member 45 in 105 which these grippers are confined, and the member 41 which is fast to the member 45 and which has a spline and slot connection 110 12, 40 with the right-hand end portion of the platen. Also it will be seen that when the finger wheel 61 is pushed in, it releases or disconnects the grippers or clutch members 64, so that if the finger wheel 61 be turned, rotary motion will be transmitted 115 from it to the platen through the shaft 60, the head 68, slot 51, member 45, member 41 and spline and slot connection 12, 40.

The usual pressure rolls 72 and 73 are associated with the platen, the rolls 72 being at the rear and the rolls 73 at the front side 120

thereof. Also the platen itself is preferably equipped with a clamping contrivance comprising, as shown in Figs. 1, 5, 6 and 8, a clamping bar 74 having a rounded under-face and a top face that is arc shaped to conform to the periphery of the platen. The bar is seated in a longitudinal depression 75 in the surface of the platen and has arms 76 extending downward from its ends, said 10 arms being pivoted at 77 to the plates 11. These arms are provided with finger pieces 78 for manipulating the clamping device or bail 74, 76, and the tail portions of the arms 76 have outwardly extending lateral pins 79 15 which are engaged by the free ends of springs 80, secured by screws 81 to the plates 11. The construction is such that the springs 80 tend to maintain the bar 74 seated in the groove 75. By pressing against 20 the finger pieces 78 the bar may be swung out of the groove against the spring pressure, allowing paper to be inserted between the bar and the platen, which paper will be gripped or clamped against the platen by 25 the bar 74 when the finger pieces are released.

In order that the platen may be conveniently manipulated when detached from the machine, there may be, and preferably 30 are, provided controlling devices comprising an oblong table or support 82 (Figs. 5 and 6) which may be mounted on posts or legs 83 and provided at its sides with adjustable angular guide members 84. Ears 85 extend 35 laterally outward from one end of the table and provide bearings for stub-shafts 86 which at their inner ends carry heads 87 formed with diametrical grooves 88 which are adapted to receive the ribs or splines 12 40 at the ends of the platen. One of the shafts 86 is provided at its outer end with a collar 90 secured by a cross pin 90^a, said collar and the companion head 87 cooperating with the companion bearing member 85 to prevent 45 endwise displacement of the shaft 86. The other shaft 86 carries a crank 91 having a hub 92 through which passes a cross pin 93 whereby the crank is secured to the shaft so that when the handle or finger piece 94 is 50 turned, the shaft and the head or bearing 87 will be turned with it.

In carrying out my reproducing method, in the present instance, the platen may be readily detached from the typewriting machine by pressing the finger pieces 39 so as to withdraw the latch tongues 29^a from engagement with the slots 35 and 42. This permits the platen to be slid out of its supports, the splines or ribs 12 being withdrawn 55 from the slot-ways or seats 14 and 40 in the respective heads or members 13 and 41. It will be understood that the heads 13 and 41 are not affected by the withdrawal or removal of the platen, but that they, together 60 with their associate parts, remain undisturbed

in the platen frame. The detached platen may then be applied to the bearings 87 on the table or support 82, 83, the finger pieces 39 being pressed in so that the latches are drawn inside the plates 11, permitting the 70 ribs 12 to be slid down into the grooves 88 of the heads 87. These heads are provided with slots 87^a in which the tongues 29^a of the latches seat when released, thus interlocking the platen at its ends with its supports 87. The construction is such that if now the finger piece 94 be operated to actuate the crank 91, the platen will be turned, being rotatively supported by the shafts 86 75 which will turn in the bearings or ears 85. 80

One or more sheets of paper 95, associated with a corresponding sheet of reproducing or duplicating material or carbon paper 96 are supported on the upper face of the table 82 between the guides 84 which are suitably 85 adjusted for cooperation with the side edges of the sheets. The work sheet 95 is or may be a form sheet of the style disclosed in the aforesaid Lewis Patent No. 932,713. Each of the forms thereon occupies a length on 90 the sheet substantially the equivalent in length to the circumference of the platen, and the form sheet may be of sufficient length to contain one, two, three or more forms, the carbon or reproducing sheet 95 being of corresponding length. The forms are of graduated lengths to compensate for the increasing periphery of the platen due to the progressive winding thereon of the form sheet; so that the several forms will 100 all be in register when the winding has been completed. As illustrated, the form sheet 95 is of a length sufficient for two forms, and wraps twice around the platen. With the platen supported on its bearings at 105 the end of the table as described, said platen is maintained with the clamp at the top, and the finger pieces 78 are actuated to open the clamp, after which the ends of the form sheet and the duplicating sheet are passed under the clamp which is then released, thereby clamping them to the platen. The platen is then rotated by means of the handle 94 in the direction of the arrow, Fig. 6, to an extent sufficient to wind the duplicating and 110 form sheets completely thereon. Next the finger pieces 39 are pressed to withdraw the latches 29, 29^a, permitting the platen to be slid out of its bearings on the table. The platen with the work sheet or form sheet 115 and carbon completely wound thereon and properly adjusted to begin the writing is next returned to the typewriting machine, the latches at the ends of the platen being held out of operation until it is slid back 120 and reconnected with the grooved members 13, 41, after which the latches are released so as to re-lock the platen in place in the machine. At the end of the winding operation and in transferring the platen to the 125 130

machine, the free end portions of the form sheet and carbon may stick up or stand away from the platen as indicated at *x* in Figs. 1 and 5. However, these free end portions will be taken care of by the feed rolls 72 and 73 and other controlling devices on the carriage frame as the platen is rotated. It will be understood that in this method of making duplicate copies it is not contemplated that the platen will make more than one full revolution. The writing may then be proceeded with, the platen being line spaced between the different lines of typewriting in the usual way, it being understood that each line printed through the regular ribbon on the outer form will be duplicated on the underlying form or forms through the carbon sheet. When the forms have been completely filled in, the platen may be again detached from the carriage, the written form and its duplicating strip may be unwound and removed, and a fresh form and duplicating strip may be wound on the platen, all in the described manner, this process being repeated as often as desired.

As has been stated, while I prefer to employ a winding mechanism for turning the platen when it is outside of the machine, such mechanism is not essential to the practising of my invention, broadly considered, a fact which I have endeavored to bring out more clearly by the illustrations designated as Figs. 9 and 10. In the construction illustrated by these figures, the platen employed, and which is designated as 97, corresponds in all respects with the platen 10 of the first described construction, except that the platen-carried clamp for the paper is dispensed with. An ordinary table or surface for supporting the platen outside of the machine may be used, but I prefer a support or plate 98 which is provided at its sides with a series of holes 99 disposed in pairs at suitable intervals and adapted to receive detachable and adjustable pegs or stops 100. The holes 99 are spaced apart lengthwise of the table at distances corresponding to the number of windings on the platen, so that the platen when rolled along the surface of the plate 98 will make a complete revolution between each of the pairs of pegs at the opposite sides of said plate. As shown herein, the stops or pegs 100 are arranged in the third pair of holes, thus allowing the platen to be rolled along the plate far enough to wind the form sheet 101 three times around the platen, the form sheet chosen for illustration being of sufficient length for this purpose and being provided with three forms. Also at the head of the first form there is a blank space equivalent in length to a quarter of the circumference of the platen, this being provided for convenience of manipulation. The platen after having been detached from the machine, as in the prior construction, is

applied to the end of the plate 98 as shown, the operator having no mechanism to assist him and relying solely on his hands. After the end of the sheet or strip 101, together with the usual duplicating sheet 102, has been wrapped partly around the platen, the platen is rolled along the plate or surface 98 by the hands of the operator, the sheet and duplicating strip winding on as it is rolled leftward. Consequently when the platen is finally arrested by the stops 100 as shown by dotted lines in Fig. 9, the work sheet and duplicating strip will be completely wound in place, as will be understood from Fig. 10, which shows the platen in the hand of the operator with the work sheet and duplicating strip fully wound thereon and ready to be applied to the typewriting machine to begin the writing.

The pins 100 not only serve as stops for the platen but also act as paper gages or guides. Preliminary to winding the paper or work form on the platen, said form is placed on the table against the guides or pins 100 and thereby is positioned properly, so that it is then only necessary to start the platen with the paper from the point of beginning to have the paper correctly wind thereon. In the drawing the paper is positioned against the pins which are located in the third set of holes, inasmuch as the paper is to be wound on the platen three times. If there are to be only two windings the paper would be gaged by the pins inserted in the second set of holes, and so on. These pins, of course, may be connected together to act as one, in the nature of a bar or fence. The construction disclosed in Figs. 9 and 10 is not claimed specifically in the present case.

From the foregoing it will be perceived that the essential of my improved method resides in adjusting the paper on the platen while it is detached or apart from the typewriting machine, so that the platen may be applied to the machine with the paper completely adjusted and ready for use.

As far as the mechanical devices are concerned they may be greatly varied and any suitable form or construction of detachable platen may be used instead of the forms herein shown.

What I claim as new and desire to secure by Letters Patent, is:—

1. The combination with the detachable platen of a typewriting machine, of a table or support, bearings on said table for said platen, platen rotating means associated with said bearings and a guide on said table for facilitating the application of paper to the platen when it is mounted on said bearings.

2. The combination with the detachable platen of a typewriting machine, said platen being provided with a paper clamp which is detachable with it, of a table or support, bearings for said platen on said table, a

handle on said table for rotating said platen, means for automatically connecting said handle with said platen when said platen is applied to said bearings, and a guide on said table for facilitating the introduction of paper from said table into the control of the paper clamp. 30

3. A platen detachable from its bearings in the typewriting machine and provided at 10 its ends with means for temporarily engaging in set relationship with a rotating mechanism fixedly arranged on a support located exteriorly of the typewriter whereby a form sheet and a duplicating sheet may be wound 15 together on said platen while it is detached.

4. A detachable platen provided at its ends with means for temporarily engaging in set relationship with a rotating mechanism fixedly arranged on a support located exteriorly 20 of the typewriter whereby a form sheet and a duplicating sheet may be wound together on said platen and whereby said platen may thereafter be disengaged from said rotating mechanism and restored to working position 25 in the typewriter with the form sheet and the duplicating sheet ready to be written on.

5. The improved method of preparing the

platen of a typewriting machine for producing manifold copies which consists in winding on the platen upon a table surface a plurality of times a work sheet and a duplicating sheet together which have previously been laid out flat on said table surface. 30

6. The improved method of preparing the platen of a typewriting machine for producing manifold copies which consists in laying the paper and duplicating strip on a plane surface to a gage and then rolling the platen thereon and winding the paper and duplicating strip the requisite number of times. 35

7. In combination with a typewriting machine, an exteriorly arranged paper and platen support, said typewriting machine being provided with a detachable platen adapted to be transferred to said support and while thereon have applied thereto the paper from the support and then returned to said typewriting machine with said paper thus applied. 40

Signed at the borough of Manhattan, city 50 of New York, in the county of New York and State of New York this 5th day of April, A. D. 1926.

JACOB FELBEL.
